BOILER CLEANER

Application filed February 2, 1927. Serial No. 165,480.

This invention is directed to an improvement in boiler cleaners, more particularly to means for removing from the interior of a boiler setting, accumulations of fuel ash and the like.

5 Figure 1 is a semi-diagrammatic side view in section taken through a boiler of the horizontal tube type, showing one form of our invention applied thereto;

10 Figure 1a is a side elevation showing our invention in applied position.

Figure 2 is a view similar to Figure 1, showing a modified baffle construction;

15 Figure 3 is a view similar to Figure 2, but showing a further form of our invention applied to remove deposits from the horizontal baffle of the boiler;

20 Figure 4 is a fragmentary plan view of the form of apparatus shown in Figure 3, the device being shown in its extended position;

25 Figure 5 is a view in longitudinal section of the ash removing means shown in Figures 1 and 2;

Figure 5a is a side view of the end portion of the cleaner element;

30 Figure 6 is a section along line 6—6 of Figure 5;

Figure 7 is a longitudinal section similar to Figure 5, but showing a still further modification of our invention;

35 Figure 8 is a section taken along the line 8—8 of Figure 7;

Figure 9 is a horizontal sectional view of the form of our invention shown in Figures 3 and 4;

40 Figure 10 is a vertical sectional view showing a still further modification of our invention similar in its general form, to that shown in Figure 9.

45 In Figure 1, the boiler A is shown mounted in the setting B above the combustion chamber C. The tube bank in this boiler consists of tubes D extending between headers E and E' and provided with the vertical baffles F and F' and the inclined baffle G to so direct the flow of gases from the combustion chamber that proper contact thereof with the boiler tubes D is secured. For cleaning the accumulations of ash and the like, which 50 form upon the inclined baffle G, we have pro-

vided the injector cleaner apparatus 1, a construction which will be hereinafter more fully explained. In order to move the accumulations lying on the baffles so that they can readily be reached by the injector cleaner, we have provided the supplementary blower pipe 3 located conveniently adjacent the junction of the inclined baffle G and the vertical baffle F. This blower pipe is provided with nozzles 5 from which steam or other suitable fluid, supplied to the blower pipe through the supply pipe 4, may be discharged along the baffle.

55 In Figure 2, the baffle G is shown provided with a recess G', in which recess, the injector unit 1 is located. This recess extends underneath the boiler tubes D and forms a convenient pocket in which ash and the like may accumulate and from which pocket the ash may be readily removed by the injector 60 unit.

65 In the form shown in Figures 3 and 4, an injector unit of different construction is shown. In this case, the unit 80, provided with the pipe 105 through which the ash accumulations are carried off, is shown mounted in the wall B² of the boiler setting. It is made up of sections telescopically arranged as shown, which are adapted to extend the unit so that it may sweep over any part of 70 the baffle G; for instance, it may be extended as shown in Figure 4, to a point closely adjacent the opposite wall B' of the boiler setting.

75 In all forms of this invention, the ash accumulations are removed by the application of suction which may be conveniently produced by the injector action of a discharging jet of steam, or the like. In the form shown, in Figure 5, steam or the like fluid, is supplied 80 through the pipe 2 to the operating head 20. This operating head 20 may be conveniently mounted from the flange 35 of the T-fitting 30. The stud 34 mounted in the flange 35 passes through the housing 31. In this housing and mounted upon the cap screw 34 is the spring 32, the tension of which may be 85 adjusted by the set-screw 33. The plate 35a is adapted to seal the opening in the T-fitting 30, the plate being held in place by means 90 95 100

of the spring 36. The operating head is in this manner supported from the T-fitting 30. The opposite end of this T-fitting is provided with flange 37 fastened as by bolts to flange 38, in which latter flange, the pipe 29 is threaded. This pipe 29 extends adjacent the accumulations of ash which it is desired to remove and is provided with a series of slots 29a through which the ash may be drawn.

10 The operating head 20 is provided with sheave wheel 6 fixed to shaft 7, the small pinion 8 being likewise fixed to this shaft and adapted to be rotated therewith when the sheave wheel is operated. This pinion 8 engages the gear 9 which is fixed as by set-screw 11 to the tube 10. This tube 10 is journaled in the head 12, the packing gland 14 and packing 13 serving to make a steam-tight connection therein. Thus, upon rotation of the sheave wheel 6, the tube 10 is caused to rotate. The valve 18 in cooperation with the valve seat 19, controls the flow of steam from the supply pipe 2 through the channel 20a, through tube 10 and thence to the discharge nozzles 25. This valve may be conveniently actuated by the same means used to rotate the tube 10. The cam 15 fixed to the gear wheel 9 by bolts 15a is adapted to depress the trigger 16 when the large gear 9 is rotated. The trigger, in turn, depresses valve stem 17, causing the valve 18 to move downwardly from its seat 19, thus permitting steam to pass from the pipe 2 to the channel 20a. It is obvious that the valve may be kept in this open condition any desired length of time, depending upon the degree of contact of the cam 15 with the trigger 16. When the trigger 16 has passed off the cam 15, the spring 21 mounted underneath the spring clip 21a, which spring clip is in turn fastened to the valve stem 17, will return the valve to the closed position. The operating head thus provides means to rotate the tube 10 and to control the supply of steam or the like to the nozzles in timed relation to the rotation of the said tube.

15 This tube 10 is provided at its outward end with the reducing fitting 22 in which is threaded the pipe 23. On the end of this pipe 23, is mounted the nozzle head 24 provided with the nozzles 25. These nozzles as indicated, discharge along the axis of the tube 28 toward the outlet end of this tube. By the discharge of steam from these nozzles 25, a powerful suction may be created on the interior of the pipe 28, which will pull the accumulations of ash and the like, through the slots 29a through the T-fitting 30 and out through a suitable exhaust pipe 41. This exhaust pipe 41, as shown, may be provided 20 with a flange 40, bolted to the lower flange 39 of the T-fitting 30.

25 In order to control the degree of opening of the slots 29a in the pipe 20, to insure a periodic suction through this pipe, we have 30 provided an inner tube 28 adapted to rotate

within the tube 29, within which tube it fits snugly. This tube 28 is provided with a series of slots 28a arranged spirally of the tube, so that upon rotation of the tube successive portions of the slots 29a in tube 29 may be ported to the interior of tube 28.

To rotate this tube 28, we have provided the spider 26 fixed as by welding to the tube 28. This spider is made up as shown in detail in Figure 6 and consists of the hub 26a fixed upon the tube 23. The spaces 26c are provided between the ribs 26b whereby the ash may readily pass from the pipe 28 to the T-fitting 30. These ribs 26b extending outwardly from the hub 26a may be fitted in notches 28c cut in the pipe 28. As an additional means of securing these ribs to the pipe 28, they may be welded thereto as hereinbefore pointed out. The hub 26a may conveniently be welded to the tube 23 as shown at 27. Rotation of the spirally ported inner tube 28 is thus secured by rotation of the tube 23 through the spider 26. Tube 23 as before described, is rotated from the sheave wheel 6 which also controls the supply of steam from the supply pipe 2 to the injector nozzle 25. We have thus provided a common means for controlling the degree of opening in the suction pipe 29 and for controlling the supply of steam or the like, to the injector nozzles 25. This means also controls the supply of steam or the like to nozzles 5 through pipe 4 which communicates with head 20 in the manner shown in Figures 1 and 2.

30 In the construction shown in Figure 7, the outer suction pipe 50 is adapted to extend through the boiler wall B² adjacent the accumulations which it is desired to remove. This pipe is closed at its outward end at 53 and is provided with the series of ports 52a, 52b and 52c, arranged in staggered relation around the pipe as shown. In this instance, the inner tube 59 provided with the ports 60a, 60b, arranged in a straight row as shown, is mounted fixedly in the L-fitting 58. This L-fitting 58 is attached to the bracket 55 fixed by studs 55a to the outside of the boiler wall. The connection between this L-fitting and bracket may conveniently be by means of the flanges 54 and 59a, which are joined by the bolts 57 as shown. The inner tube 59 may be threaded as at 56 to the L-fitting 58. In this case, the outer pipe 50 may be rotated by means of a wheel 61 fixed thereto by means of a set-screw 61a passing through the hub of the wheel. The hand wheel 61 thus provides means to rotate the outer ported tube 50 and thus control the opening of the ports 60, 60a, etc., in the inner stationary tube 59. The concentric tubes are shown as mounted in the wall box 51 passing through an opening in the boiler wall B². In the L-fitting 58 is provided a steam discharge nozzle 66 adapted to discharge along the longitudinal axis of the exhaust 35

pipe 64. This nozzle 66 may be supplied with steam or the like through the pipe 66a rotatably passing through the packing gland 67 mounted in the boss 67a of the L-fitting 58. This pipe 66a is joined by swivel 68 to the stationary supply pipe 69. Control of steam to the injector nozzle is accomplished by means of the valve 70 in the stationary supply line.

10 The discharge of steam from the nozzle 66 along the axis of the exhaust pipe 64 creates a suction through the L-fitting 58 pulling in the ash accumulations through whatever of the ports 60a, 60b, etc., are in register with the ports 52a, 52b, 52c, etc. It frequently happens that these ports become clogged with accumulations of ash and the like and it thus becomes desirable to provide means whereby they may be readily cleaned when desired. 15 This can be most conveniently accomplished by a discharge of steam or the like through the pipe 59 and through the ports. To accomplish this, we have provided the handle 71 fixed to the supply pipe 66a, in which supply pipe the nozzle is mounted. By oscillating this handle, the steam discharge nozzle 68 may be swung through ninety degrees to the position shown in dotted lines in Figure 7. The discharge of steam will thus be longitudinally of the pipe 59 and through the registering ports as 60b and 52b, which ports may thus be cleared of any accumulations. In order to increase the force of the steam through the pipe 59, we may provide in the 20 exhaust pipe 64, the slide member 65. Thus, when the steam is discharged into pipe 59, the slide 65 may be closed to prevent the escape of steam from the discharge pipe 64, thus aiding in the removal of accumulations of ash or the like from the ports of the suction tubes by maintaining a suitable pressure in the pipe 59.

Describing now the form shown in Figure 9, 81 is an extended suction fitting provided 25 with the inlet 82 and adapted in the operation of the device to move over the surface of the baffle G. As shown in Figures 3 and 4, this device is mounted in the wall of the boiler setting and is adapted to be projected by any suitable means to sweep over the surface of the baffle. The means to extend the device will now be described. The sheave wheel 89 is fixed to the tube 91 and can be rotated in any suitable manner. Fixed to this same tube 91 is the sprocket wheel 96, which with the sprocket chain 97, is adapted to rotate the sprocket wheel 96a and the tube 91a. Thus the two extending members, one on each side of the device, are operated in unison. In 30 the opposite end of the tube 91 are cut the recesses 97 adapted to engage the square teeth 98 formed spirally on the tube 99. This tube 99 is enclosed in a suitable housing 100, slidably fitted over the tube 91. By rotation of the tube 91, the tube 99 may thus be moved lon-

gitudinally to extend or withdraw the suction fitting 81 as desired. At the inner end of tube 99 is fitted the closure member 101 threaded to receive the screw member 102. This member, in turn, is enclosed in the housing 103 and is fixed at 104 to the suction member 81. Thus, when the end of the tube 91 has passed over all the threads of the tube 99, the member 99 then starts to rotate. By this rotation, the threaded member 102 feeds through the member 101, thus permitting a further movement of the suction member 81.

To produce a suitable suction in the member 81 and through the nozzle 82, a steam discharge nozzle 85, fitting in the pipe 86 is provided. This may be located in the discharge pipe 105, so as to discharge along the axis of this pipe in a downward direction. Steam to this nozzle may be supplied through pipe 87 controlled by valve 88. The discharge pipe may be fitted to the L-84 in any suitable manner. On the other arm of this L, flange 95 is fixed to flange 94 as shown. Threaded in this flange 84 is the innermost telescoping member 83b. Arranged to telescope inside this member is the second pipe 83a, the outermost pipe 83 being adapted to telescope with this second member in like manner. The outermost member 83 is fixed to the suction member 81 as shown. The various telescoping discharge pipes are provided with collars 92 adapted when the pipes are fully extended, to engage the shoulder 93 of the inner telescoping pipe. By means of this telescoping discharge pipe, a suitable connection is maintained between the suction member 81 and the discharge pipe 105 in any position of this suction member.

In Figure 10, the construction shown is similar, except that only one operating screw is shown and this is located inside the telescoping discharge pipes. The suction member 111 provided with nozzle 112 is adapted to extend across the baffle as desired. The operating screw 129 is fitted to the spider 131, which spider is provided with openings 132 for the passage of ash and the like into the telescoping discharge pipe 113. This telescoping pipe 113 fits inside 113a, which in turn, is adapted to telescope inside the third pipe 113b. This pipe in turn, is fixed to flange 118, which flange is fixed to flange 122 of the T-fitting 114. Suitable suction is produced by means of discharge of steam or the like from the nozzle 115, discharging downwardly along the axis of the discharge pipe 117. The operating tube 121 is provided at its one extremity with the square threads 126 adapted to engage the member 127. This, in turn, is fitted at its end with a threaded closure member 128 threadedly engaging the member 129. Thus, by rotation of the tube 121, the suction member 111 may be projected and withdrawn as desired. Rotation of tube 121 may be conveniently carried out by actu-

ation of the sheave wheel 119 fixed to the tube, chain 120 being fitted to the sheave wheel. The tube 121 passes through fitting 124, flanged at 125 to the T-fitting 114, the gland 123 being provided if desirable to secure a tight fitting in the member 124.

In either of the forms shown in Figures 9 or 10, the suction member is adapted to be projected across the baffle or other part of the boiler to clean therefrom the accumulations of ash or the like. The discharge pipe from the suction member is, in this instance, telescopically arranged so that a suitable suction produced by the injector action of a steam jet or in any other suitable manner is always operative at the nozzle of the suction member.

For the sake of convenience, this invention has been described as being embodied in a boiler furnace cleaner for cleaning parts of a boiler furnace. It will be apparent, however, that the invention may be embodied in a cleaner for any similar type of apparatus, and it is to be therefore understood that the term "boiler furnace" wherever used in the specification or claims is to be construed as meaning a furnace for a heat transfer apparatus or fluid heater of any character, while the term "boiler furnace cleaner" is to be construed as meaning a cleaner for any such apparatus. It is to be further understood that the term "boiler furnace" wherever used is to be construed as meaning a boiler setting, the combustion chamber enclosed by the boiler setting, and the baffles utilized for determining the flow of the gases around the boiler parts.

What we claim as our invention is:

1. In a boiler associated with a furnace, the combination with a plurality of boiler tubes and a baffle located in proximity to said tubes for directing the furnace gases thereabout, of a hollow member mounted adjacent the baffle, a port in said member, means to diminish the pressure within said member, and means adapted to move toward the said port, deposits normally lying at a distance therefrom.

2. In a boiler, the combination with a baffle, of a hollow member mounted adjacent the baffle, a port in said member, means to diminish the pressure within said hollow member, means adapted to move toward the said port, deposits normally lying at a distance therefrom, and means for actuating said last-named means in unison with the said first-named means.

3. In a boiler associated with a furnace, the combination with a baffle, of a suction device mounted adjacent the baffle and adapted to remove therefrom deposits formed in the operation of the furnace, means adapted to move toward the said suction device, deposits normally lying at a distance therefrom, and a common means to control the op-

eration of said last-named means and of said suction device.

4. In a boiler associated with a furnace, the combination with a plurality of boiler tubes and a baffle adjacent said tubes for directing the furnace gases toward said tubes and provided with a recess, of a suction device mounted in the recess and adapted to remove therefrom deposits formed in the operation of the boiler, and means adapted to move toward the said recess, deposits normally lying at a distance therefrom. 70

5. In a boiler associated with a furnace, the combination with a baffle provided with a recess, of a suction device mounted in the recess and adapted to remove therefrom deposits formed in the operation of the furnace, means adapted to move toward the said recess, deposits lying at a distance therefrom, and common means to control the operation of said last-named means and of said suction device. 80

6. In a soot extractor for boilers, a hollow member extending adjacent the parts of the boiler to be cleaned, said member being provided with a port, means to produce a suction within the said member, means controlling said suction producing means, means to control the opening of the port in said member, and a common means to control the operation of said suction control means and of said port control means. 90

7. In a soot extractor for boilers, a stationary hollow member extending adjacent the parts of the boiler to be cleaned, said member being provided with ports, means to diminish the pressure within said member, means to control said pressure diminishing means, a second member provided with a port adapted to register with certain of the ports in said first-named member and movable to control the registration of said ports and a member movable to control the said control means and to move said second mentioned member. 100

8. A suction cleaner adapted to remove from the interior of a boiler setting deposits formed in the operation of the boiler furnace, said cleaner comprising a hollow member provided with ports, means to produce a suction on the interior of said hollow member by the discharge of a fluid such as steam, means to control the discharge of the suction producing fluid, means to control the opening of the ports in said member, and a common means for actuating said two control means. 115

9. In a soot extractor for a boiler furnace, a suction member associated with a portion of said boiler furnace, a blower element arranged to discharge a fluid under pressure over the surface of said portion of the boiler furnace and toward the suction member to move deposits on the surface of the said portion of the boiler furnace toward the 125

suction member, a source of fluid under pressure, and a common means for controlling the flow of fluid under pressure from said source to said suction member and to said 5 blower element to simultaneously effect a discharge of fluid from said blower element and create a suction in said suction member.

10. In combination, a boiler furnace, a blower element, a suction device cooperating 10 with said blower element to remove soot from a portion of the boiler furnace, said blower element being arranged to move deposits on the surface of the said portion of the boiler furnace toward the suction member, and a 15 common means for controlling the operation of said blower element and said suction device.

11. In a soot extractor for a boiler furnace, a ported suction member associated with a 20 portion of said boiler furnace, means to control the opening of the ports in said member, a blower element so associated with the said portion of the boiler furnace as to move deposits on the surface thereof toward the ports 25 in the said suction member, and common means for controlling the operation of said suction member, blower element, and port control means.

In testimony whereof I affix my signature.

30 WILLIS P. THOMAS.

In testimony whereof I affix my signature.

NORMAN L. SNOW.
